UNITED STATES PATENT OFFICE.

SAINT MINUTOLI, OF HOUSTON, TEXAS.

DISPLAY DEVICE.

1,413,483.

Specification of Letters Patent. Patented Apr. 18, 1922.

Application filed February 12, 1921. Serial No. 444,410.

To all whom it may concern:

Be it known that I, SAINT MINUTOLI, a citizen of Italy, residing at Houston, in the county of Harris and State of Texas, 5 have invented new and useful Improvements in Display Devices, of which the following is a specification.

This invention relates to display devices and has for its object the provision of a 10 device adapted to contain and attractively display boxes of cigars, the wooden cigar-box cover being replaced by a glass pane forming a part of my device and permitting free view of the cigars so that their color 15 and shape may be ascertained while preventing them from being handled by the prospective purchaser and protecting them against dust.

An important object is the provision of a 20 device of this character into which the cigar box is bodily inserted, the device being therefore simple and inexpensive in construction, as well as highly efficient and durable in use, and a general improvement in 25 the art.

With the above and other objects and advantages in view, the invention consists in the details of construction to be hereinafter more fully described and claimed and 30 illustrated in the accompanying drawings in which—

Figure 1 is a perspective view of my device in use,

Figure 2 is a front elevation thereof with 35 the glass cover swung into open position, and

Figure 3 is a cross sectional view.

Referring more particularly to the drawings, the letter A designates a box of cigars 40 to be displayed, the box having the usual cover B. In carrying out my invention I provide a casing which includes end walls 10 which have inclined forward and rear upper edges 11 and 12, respectively. Dis- 45 posed and secured between these end walls is a transverse member 13 which is adapted to support the bottom of the cigar box A, and secured to and projecting downwardly and forwardly from this transverse member 50 is an arm 14 having its end formed with an upturned retaining flange or lip 15 for holding the cigar box in position. When

the box is placed upon the transverse member 13 and arm 14 the folded back cover B of the box will be substantially parallel 55 with the upper inclined edges 12 of the end walls and will form a back for the casing.

Extending through the end walls 10 is a 60 rod or shaft 16 through which are formed transverse holes 18 disposed outwardly of 65 the end walls for the reception of cotter pins 19 or the like which prevent the rod from longitudinal displacement. The numeral 20 designates a preferably metallic rectangular frame within which is a sheet of glass 21. 65 The frame is adapted to engage against the inclined edges 11 of the end walls to form a cover for the casing and this frame is formed at two corners with ears 22 provided with holes 23 for the passage of the rod 16. 70

With the parts constructed and assembled as above described, it will be seen that when the cigar box A is placed in the device it will be firmly held in inclined position with the frame 20 covering the open top of the box, 75 it being of course necessary that the ordinary wooden cover of the box be either removed or else swung rearwardly to leave the top open. It will be seen that the cigars will be fully displayed so that their quality, 80 color, etc., may be ascertained and at the same time they will be protected against dirt and handling.

While I have shown and described the preferred embodiment of my invention, it is 85 of course to be understood that I reserve the right to make such changes in the form, construction, and arrangement of parts as will not depart from the spirit of the invention or the scope of the subjoined claim. 90

Having thus described my invention, I claim:

A display device of the character de- 95 scribed comprising a pair of upstanding end walls having their front and rear edges in- clined and converged upwardly, a forwardly and downwardly inclined transverse bar se- 100 cured to and connecting said end walls at intermediate portions thereof with the rear edge of said bar being disposed adjacent the lower corner of the inclined rear edges of 100 the end walls, a rod extending transversely through said end walls at the highermost points thereof, an arm secured upon said

transverse bar and extending forwardly and downwardly and terminating in an upturned retaining flange, the device being designed to receive a cigar box placed upon 5 said transverse bar with its front wall engaged by said flange and with its ends engaging against the inner faces of said end

walls, and a glass carrying frame designed to fit between the end walls and formed with ears revolvably engaged upon said rod, said frame engaging upon the upper edges of 10 the ends of the cigar box.

In testimony whereof I affix my signature.
SAINT MINUTOLI.
